UNITED STATES PATENT OFFICE.

BENJAMIN L. BRADLEY, OF BALTIMORE, MARYLAND, ASSIGNOR TO MAX NUSBAUM, OF BALTIMORE, MARYLAND.

VARNISHING-MACHINE.

No. 911,471.

Specification of Letters Patent.

Patented Feb. 2, 1909.

Application filed February 5, 1907. Serial No. 355,850.

To whom it may concern:

Be it known that I, BENJAMIN L. BRADLEY, a citizen of the United States, residing at Baltimore city, in the State of Maryland, have invented a new and useful Improvement in Varnishing-Machines, of which the following is a specification.

My invention relates to improvements in molding varnishing machines.

10 The object of my invention is to provide a machine of the character described in which the molding is fed continuously through the machine in an inverted position and the varnish applied to the lower face thereof evenly and as it passes from the machine the surplus varnish is rubbed therefrom to give to the molding an even smooth finish.

15 I also provide a machine with which moldings of different widths and thicknesses can be readily varnished.

20 Another object of my invention is to provide a more simple cheap and effective machine of this character as will be hereinafter fully described.

25 In the accompanying drawings, Figure 1, is a side elevation of my improved machine. Fig. 2, is a top plan. Fig. 3, is an end view looking from the end of the machine in which the molding is fed as indicated by the arrow Fig. 1. Fig. 4, is an enlarged vertical sectional view of the varnish containing receptacle showing the rotary brush in side elevation. Fig. 5, is a vertical sectional view of the varnish containing tank and from 30 which the varnish is fed to the receptacle.

35 Referring now to the drawings, 1, represents a rectangular frame composed of vertical standards or legs 2 and 3, on each side and connected together by the transverse bars 4 and 5 at each end and the standards at their upper ends are also connected together by the longitudinal horizontal bars 6 and 7 and below the same by bars 8 all of which form the rectangular frame 1 for supporting the numerous parts of the machine.

40 Carried by the upper horizontal beam 6 of the frame are two outwardly extending brackets 9 and 10, which extend a considerable distance outwardly, and are provided with vertical elongated slots 11, extending longitudinally thereof. These brackets form the support and guide for the molding as it is being fed through the machine. Resting upon these brackets are longitudinally extending guide rails 12 and 13, through which

vertical bolts pass above the brackets. Said bolts extending through the slots 11 and whereby the guide rails may be adjusted transverse of the machine, or to and from each other to receive moldings of different widths. The outer rail 13 is provided with an upwardly extending flange 14 which extends sufficiently high to go beyond the rounded enlarged portion of the molding whereby it serves as an accurate guide for 65 the molding.

The lower faces of the beams 6 and 7 are provided with journals in which is mounted a transverse shaft 15 which on the outside of the frame is provided with a large drive pulley 16 by means of which the shaft is rotated. At the feed end of the frame the standards 2 are provided with journals 17 in which is mounted a shaft 18, and the said shaft intermediate the standards is provided with the 70 pulleys 19 and 20 over which the belt 21 passes. Said belt is driven by any desired motor and by means of which the entire machine is driven. The shaft 18 extends beyond the frame and has keyed thereon a 75 small pulley 22 and a larger pulley 23. The pulley 22 is in alignment with the pulley 16. Passing around said pulleys is a belt 24 by means of which the shaft 15 is slowly rotated owing to the relative sizes of the two pulleys. 80

The shaft 15 intermediate the beams 6 and 7 is provided with a small gear wheel 25 mounted on the lower face of the beams 6 and 7. On opposite sides of the shaft 18 are shafts 26 and 27 which have gears 28 and 29 90 carried thereby and which mesh with the gear 25 and said gears being larger than the gear 25 the shafts 26 and 27 are caused to rotate slowly in the same direction. The shafts 26 and 27 extend out beyond the side 95 of the frame and are provided with feed rollers 30 and 31, which are of a width and diameter to extend upwardly between the guide rails 12 and 13 and engage the molding 32, and whereby the same is fed longitudinally through the machine.

The beams 6 and 7 are provided with two upwardly extending sets of brackets 33 and 34. The two brackets 34 carried by the beams 6 and 7 are oppositely arranged and have bolted thereto the transverse bar 35, by means of bolts 36. The said bar 35 extends a distance beyond the side of frame equal to that of the brackets 9 and 10, and is provided with a longitudinal elongated slot 37. Car- 110

ried by said bar is a roller carrying frame 38. The said frame is composed of the horizontal arms 39, in which is mounted the friction roller 40, which is adapted to engage the upper face of the molding, directly above the feed roller 31 and firmly holds it thereon so that it will be properly fed forward.

The vertical portion 41 of the roller carrying frame is provided with a vertical slot 42 10 and passing through the slot 37 in the bar 35 and the slot 42, is a clamping bolt 43, which firmly clamps the said frame in its adjusted position. By the arrangement of the two slots it will be seen that the roller can be adjusted vertically when using molding of different thicknesses and can be adjusted in or out so as to centrally engage the said molding.

The wheel 40 is preferably shown grooved to correspond to that of the back of the molding so as to more firmly hold the molding in 20 its downward position upon the feed roll.

The brackets 33 carry a bar 44, which carries a wheel frame 45. Said frame carries the wheel 46 which is directly above the 25 wheel 31 and is mounted the same as the frame 41 to have a vertical and horizontal movement, all of which has been fully described in respect to the frame 41.

The standards 3 on the inside are provided 30 with a bearing in which is mounted a shaft 47 which extends beyond the frame at both ends. At one end said shaft is provided with a pulley 48 which is in a line with the pulley 23. A belt 49 passes around said pulley by 35 means of which the shaft 47 is rotated. The said shaft on the opposite side of the frame is provided with a wheel like member composed of a hub 50, having a series of spokes 51, which carry at their outer ends brush 40 clamping members 52, which are adapted to clamp and hold the varnish brushes for applying the same to the under side of the molding. The said clamping members are formed by transverse bars 53 carried by the 45 spokes and provided with bolts 54, which pass through bars or plates 55, corresponding with the bars 53 and by means of the bolts the ordinary paint brush 56 may be readily clamped and whereby brushes of different 50 widths may be used when varnishing moldings of different widths. The said brushes are so arranged that their upper ends or bristles extend slightly above a plane with the upper face of the brackets, and whereby 55 the varnish is applied to the lower face of the molding.

The horizontal bar 8, directly below the brush member is provided with the varnish containing receptacle 57, which by means of 60 the bracket 58 is vertically adjustable. The said tank is of an elongated form and so positioned that the brush carrying arms pass within the same adjacent to the lower end and from this receptacle the brushes are fed 65 with the varnish. The receptacle 57 adja-

cent one corner, is provided with a transverse bar 59, which carries a scraper 60, which is adjustably held by a set screw 61, whereby it is adjusted up and down. This scraper is in the path of rotation of the 70 brushes and is adapted to scrape the surplus varnish from the brushes, to prevent too much being applied to the molding. The amount of varnish is regulated by the adjustment of the scraper. I have shown two 75 other scrapers 62 and 63, which can be used to more thoroughly accomplish the result of limiting the amount of varnish applied. The frame 1, also carries a spreader 64, which is in the path of rotation of the brushes. 80 The bristles thereof engage the spreader and evenly spread the varnish on the brushes so that the varnish will be evenly spread upon the molding. The varnish is supplied to the receptacle 57 from a tank 65, supported upon a bracket 66, carried by the upper face of the frame. A pipe 67 leads downwardly from the lower end of the tank to the receptacle, and the said pipe below the tank is provided with a cock 68 for cutting off the supply 90 of varnish to the receptacle.

In order to keep a determined amount of varnish in the receptacle, and to automatically feed the oil thereto, as it is used by the brushes, I make the tank 65 perfectly air 95 tight and connect to the upper end thereof a pipe 69, which leads downwardly and is connected to the side of the receptacle as indicated at 70. The said connection 70 is at a point at which the desired amount of varnish 100 is desired in the receptacle. As the varnish is used the connection 70 is opened so that air passes into the pipe 69 and to the tank 65, and allows the varnish to flow to the receptacle through the pipe 67 and when the 105 varnish has risen in the receptacle to close the connection 70, the air is shut off from the tank and the flow of varnish is stopped.

Secured to the beams 6 and 7 are brackets 71, which have bolted thereto the transverse bar 72 similar to the bars 44 and 35, and has an elongated slot in its end beyond the frame. The said bar carries a keeper 73, which is secured thereto by means of a bolt 74, and said keeper bears upon the upper 110 face of the molding and holds the molding firmly down upon the brushes so that the varnish will be applied to all parts thereof. The beams 6 and 7, are provided with brackets 75, adjacent the ends opposite the feed end and carrying a bar 76, which is provided with a slot and a wheel carriage 77, vertically and horizontally adjustable the same as the carriages 45 and 41 heretofore described. The said carriages have a wheel 78 bearing upon the upper face of the molding whereby the molding is firmly held down upon the rubber which is supported by the frame. Said rubber may be of any desired material and its upper face is formed of a 115 120 125 130

curvature to correspond with the molding and the rubber is adapted to remove all surplus varnish therefrom and give a finish to the molding.

5 The molding, as before stated, is fed to the machine from the right as shown by arrow, Fig. 1. It is first placed upon the bracket 9 between the guide rails 12 and 13 and is pushed forward and engaged by the roller 10 40, which holds it down upon the feed roller whereby the molding is fed forward to the second feed roller 31 and the roller 46 and is continued to be fed forward. The molding is next engaged by the presser 73 which 15 holds it down upon rotary brush whereby the varnish is applied to the molding. The molding is next engaged by the roller 78 which holds the molding down upon the rubber 79 and the molding comes from the 20 machine completed. Moldings of this character as well understood, are in pieces of considerable length and these pieces are fed in a continuous line through the machine.

What I claim is:—

25 1. A molding varnishing machine, comprising a frame, means for feeding the molding in a horizontal position along said frame, a rotary brush composed of a hub-like member having radial arms, brush 30 clamping members carried by the ends of said arms, brushes carried by said members and means for applying varnish to said brushes.

2. A varnishing machine comprising a 35 frame, means for feeding the molding in a horizontal position along said frame, a rotary brush composed of a hub like member having radial arms, transverse brush clamping members carried by the ends of said arms, 40 ordinary paint brushes clamped by said members, and means for supplying varnish to said brushes.

3. A varnishing machine, comprising a 45 frame, means for feeding the molding in a horizontal position along said frame, a rotary brush composed of a hub-like member having radial arms, transverse plates carried by the ends of said arms, bolts carried by 50 said plates and carrying plates parallel with the plates carried by the arms, paint brushes clamped between said plates by the bolts, and means for supplying varnish to the brushes.

4. A varnishing machine comprising a 55 frame, brackets carried by one side of the frame, guide plates carried by the brackets and adapted to be adjusted for receiving moldings of different widths, a transverse shaft extending through the frame, means 60 for rotating said shaft, a gear carried by said shaft, a shaft carried by the frame on each side of the first mentioned shaft and having gears meshing with the gears carried thereby, feed rollers carried by said shafts below the 65 guide plates, brackets carried by the frame,

a horizontal bar carried thereby and extending out above the guide plates, pressure rollers carried by said arm and horizontally and vertically adjusted, a rotary varnish brush, and means for rotating said brush. 70

5. A varnishing machine, comprising a frame, means for feeding the molding horizontally along the frame, a rotary varnishing brush, a keeper above the brush for holding the molding upon the brush, means for 75 horizontally and vertically adjusting said keeper, a rubber conforming to the curvature of the molding, and a pressure roller above the rubber and adapted to hold the rubber on the molding and means for horizontally and vertically adjusting said roller. 80

6. A varnishing machine, comprising a frame, feed rollers carried by one end, a rubber adjacent the opposite end, a rotary varnish brush intermediate the rubber and 85 feed rollers the upper end being in an approximately horizontal plane, the vertical brackets carried by the frame and having a separate horizontal bar extending over the feed rollers, the varnish brushes and the 90 rubber, the outer end of said bars having a horizontal slot, a pressure carriage having a vertical slot, and bolts passing through the slot in the bars and the carriages whereby the pressure carriages are horizontally and 95 vertically adjustable for operating on moldings of different widths and thicknesses.

7. A varnishing machine, comprising a frame, means for feeding the molding horizontally upon the frame, a receptacle carried 100 by the frame, a rotary brush mounted upon the frame and having its lower end rotating within the receptacle, a transverse bar carried by the receptacle, scrapers carried by the bar and adjustable in or out of alinement 105 with the line of rotation of said brush, and a spreader above the receptacle and adapted to spread the varnish evenly upon the brush heads.

8. A molding varnishing machine, comprising a frame, means for feeding the molding in a horizontal position along said frame, a rotary varnishing brush composed of a hub-like member having radial arms having a transverse elongated plate at their ends, 110 a removable transverse plate, transverse bolts passing through the ends of said plates, and a brush between said plates and adapted to be clamped between the plates by the bolts, and means for supplying varnish to 115 said brushes.

9. A molding varnishing machine comprising a frame, means for feeding the molding in a horizontal position along said frame, a rotary varnishing brush composed of a hub-like member having radial arms having a transverse elongated plate at their outer 125 ends, a removable transverse plate, transverse bolts passing through the ends of said plates, a brush between said plates and 130

adapted to be clamped between the plates by the bolts, a tank below the hub and into which the arms extend, a radially-extending scraper carried by the tank, a circular spreader above the tank for engaging the brushes, and spreading the varnish and means for automatically keeping determined amounts of varnish in the tank.

10. A molding varnishing machine, comprising a frame, means for feeding the molding in a horizontal position along said frame, a rotary varnishing brush composed of a hub-like member having radial arms having a transverse elongated plate at their ends, 15 a removable transverse plate, means for clamping the ends of said plate together and a brush between said plate and adapted to be clamped between the same by the clamping means, and means for supplying varnish 20 to said brushes.

11. A molding varnishing machine com-

prising a frame, means for feeding the molding in a horizontal position along said frame, a rotary varnishing brush composed of a hub-like member having radial arms, means 25 for securing brushes in the ends of said arms, feed rollers below the table, vertically and horizontally adjustable pressure rollers above the table, a tank below the hub and into which the arms carrying the brushes extend, 30 a radially extending scraper carried by the tank, a circular spreader above the tank for engaging the brushes and spreading the varnish, and means for automatically keeping a pre-determined amount of varnish in 35 the tank.

In testimony whereof I affix my signature, in presence of two witnesses.

BENJAMIN L. BRADLEY.
